AIR SUPPLY MEANS FOR LIFE PRESERVERS

Harry B. White, Wilmington, N. C.

Original application March 27, 1943, Serial No. 480,821. Divided and this application October 21, 1943, Serial No. 507,138

2 Claims. (Cl. 9—17)

This invention relates to new and useful improvements in life preservers and more particularly to novel means for supplying air thereto.

The principal object of the present invention is to provide a life preserver containing a reservoir or container for air or expansible gas which can be liberated into the preserver proper during an emergency.

Further, the present application is a division of my co-pending application Serial No. 480,821, filed March 27, 1943, for Life saving apparatus.

Other objects and advantages of the invention will become apparent to the reader of the following description.

In the drawings:

Figure 1 is a horizontal sectional view through the life preserver showing the air supply means.

Figure 2 is a section on the line 2—2 of Figure 1.

Figure 3 is an enlarged fragmentary detailed sectional view taken on the line 3—3 of Figure 1.

Figure 4 is a perspective view of one of the air containers.

Figure 5 is an elevational view of one section of the valve.

Figure 6 is an elevational view of the other section of the valve.

Referring to the drawings wherein like numerals designate like parts, it can be seen that numeral 5 denotes an annular body encircling tube which may be constructed as shown in Figure 1. Inside of the annulus 5 at a pair of diametrically opposite points, are horizontal shelves 7 and rising from these shelves 7, which are preferably perforated, are rectangular-shaped wall structures 8, each having a transverse partition 9 adjacent one end to divide the interior of the wall into chambers 10 and 11.

The chamber 11 contains a receptacle 12 of a form to conform with the curvature of the annulus 5, this receptacle 12 preferably having a threaded neck 13 at one end adapted to be connected by a coupling element 14 to a gooseneck 15, which extends through the corresponding partition 9 and terminates in the compartment 10 over a valve unit generally referred to by numeral 16, this valve unit 16 being made up of an upper fixed section 17 and a lower rotatable section 18, the upper section 17 having a depending lug 19 which rides in a short slot 20 of the lower section 18. These sections 17 and 18 are connected by a screw element 21 passing through central openings 22 in the sections and these sections are formed with registrable openings 23, 24.

A control shaft 25 is vertically disposed in the

compartment 10 but extends downwardly through a packing gland 26. This shaft 25 is provided with a handle 27 at its upper end and with an arm 28 at its lower end for engagement with the rotatable valve element 18.

It can be seen that underlying each shelf 7 is a transverse partition 29 supporting a packing coupling 30, this receiving the lower valve element 18. With these partitions 29 at diametrically opposite portions of the interior of the annulus 5, the annulus 5 is divided into a pair of air chambers A—B, and when the openings 23, 24 of the valve 16 register, air from the air receptacles 12 (or receptacle if only one is being used at a time) is supplied to both chambers A—B.

It can be seen that each of the wall structures 8 rises to the perimeter of an opening 31 in the top of the annulus 5 and a closure plate 36 is provided for each of these openings, the closure plates being disposed over suitable packing element 37 and provided with suitable hinges 40 and detent means 38.

It should be seen that the packing gland 26 for the valve shaft 25 and for supporting the valve structure 16 and the gooseneck 15 is mounted on a movable plate 39 secured in place to the shelf by screws 40.

The valve units 16 are normally closed. When it is necessary to do so, air may be supplied to the chambers A, B by rotating any valve section 18 to align the openings 23, 24 therein with the corresponding openings 23, 24 in the valve section 17 so that air in the receptacle 12 controlled by the valve unit 16 thus opened may discharge from said receptacle through neck 13 and gooseneck 15 into said chambers through the thus opened valve unit 16. This opening of a valve unit 16 may be accomplished by opening the closure plate 36 and turning the appropriate shaft 25 in the proper direction.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a life saving device, an air tight annulus, 50 a perforated shelf in said annulus, a rectangular wall structure on said shelf having a partition therein dividing the structure into a pair of relatively large and small chambers, a storage receptacle for compressed air disposed in the large 55 chamber, a valve in the small chamber depend-

ing therefrom below the shelf, a detachable connection between the receptacle and valve extending through the partition, and means to operate said valve comprising a controlling shaft in the small chamber.

2. In a life saving device, an air tight annulus, a perforated shelf in said annulus, a rectangular wall structure on said shelf having a partition therein dividing the structure into a pair of relatively large and small chambers, a storage receptacle for compressed air disposed in the large

chamber, a valve in the small chamber depending therefrom below the shelf, a detachable connection between the receptacle and valve extending through the partition, means to operate said valve comprising a controlling shaft in the small chamber, and a transverse supporting partition in the annulus underlying the shelf and dividing the annulus, said valve communicating with the annulus upon both sides of said last partition.

HARRY B. WHITE.
